UNITED STATES PATENT OFFICE.

HANS HOLDEN JENSEN, OF MILWAUKEE, WISCONSIN.

DESIGN FOR AN ANTIRATTLING DEVICE.

47,851.

Specification for Design.

Patented Sept. 21, 1915.

Application filed April 5, 1915. Serial No. 19,385. Term of patent 14 years.

To all whom it may concern:

Be it known that I, HANS HOLDEN JENSEN, a citizen of the United States, residing at Milwaukee, in the county of Milwaukee and State of Wisconsin, have invented a new, original, and ornamental Design for an Antirattling Device, of which the following is a specification, reference being had to the accompanying drawing, forming a part thereof.

Figure 1 is a perspective view of an anti-rattling device, showing my design. Fig. 2 is an edgewise view of the same.

I claim:

The ornamental design for an anti-rattling device, as shown.

HANS HOLDEN JENSEN.

Witnesses:

ALFRED KLINGELHOEFER,
M. VON BERGEN.
